FILLING-FEELER MECHANISM FOR LOOMS.

Application filed February 8, 1927. Serial No. 166,700.

The present invention relates to an improvement in filling feeler mechanisms for looms.

The object of the invention is to produce an improved filling feeler, and to this end the invention consists in the feeler herein-after described and particularly defined in the claims.

In the accompanying drawings illustrating the preferred form of the invention, Figs. 1 and 2 are plans illustrating the filling feeler mechanism in different positions; Fig. 3 is a section taken on the line 3—3, Fig. 1; Fig. 4 is a side view of the latch lever as viewed on the line 4—4, Fig. 2, and the outer end of the weft replenishing actuator; and Figs. 5, 6 and 7 illustrate a modified form of the feeler, Fig. 6 being a section taken on the line 6—6, Fig. 5, and Fig. 20 7 being a section taken on the line 7—7, Fig. 5.

The illustrated embodiment of the invention is described as follows: The loom to which this filling feeler mechanism is attached may be of any usual or improved construction, the lay 10 supporting the shuttle 11 in the usual manner. The loom is provided with weft replenishing mechanism indicated in a general way by the reference character 12, applied to the change shaft. The loom has a weft hammer 13 provided with a bifurcated head, of which one finger 14 is provided to engage the latch lever 15 pivoted on the weft replenishing actuator 16, and of which the other head 17 is adapted to engage the tail of the weft fork 18. The weft replenishing actuator 16 is pivotally attached at 20 to the arm 21 whose hub 22 is secured to the change shaft 12. When the latch lever 15 is turned to the right it is moved in front of the face of the finger 14 of the weft hammer, and the latter pushes upon the latch lever to force the weft replenishing actuator 16 forwardly so as to turn the change shaft and cause weft replenishment to be performed.

The filling feeler is mounted on a bracket 23. The feeler has a frame 24 which is bolted at 25 to the bracket 23. This feeler frame carries the feeler 26, which has its

filling feeling end offset with respect to its body 27. The body is pivoted at 28 in a slot 30, the pivot pin 28 of the feeler entering the slot 30 being adapted to slide back and forth therein. A spring 31 in the slot 30 normally presses against the pivot pin 28 of the feeler and tends to hold it in the rear end of the slot in position to engage the filling 32 on the filling carrier or bobbin 33, carried by the shuttle 11. The front of 60 the shuttle is slotted at 34 in the usual manner.

The body of the feeler is provided with a little projection 35 on one side, and with a flat face 36 on the other side. The projection 35 engages the guide wall 37, being held against that wall by the trip lever 38. The trip lever has a downwardly extended spring seat carrying boss 40, which extends downwardly from the lever proper into the 70 slot 30, the two ends of the spring being received the one in the pivot 28, and the other in the spring seat recess 40 of the trip lever 38. The trip lever is pivoted at 41 upon the frame 24, and is normally held in the 75 position shown in Fig. 1 by the spring. The trip lever is provided with an ear 42 to which is attached one end of the link 43, the other end of which is attached to the latch lever at 44.

The left hand side of the trip lever engages the flat side 36 of the feeler body and normally tends to hold the feeler in the position shown in Fig. 1. When the feeler strikes the filling on the carrier, it is pushed 85 forwardly from its normal rearward position to that illustrated in Fig. 1, which shows it in a forward position. Pressure of the filling on the opposite end of the filling feeler tends to turn the feeler about the pivot, and so long as sufficient filling is engaged by the teeth on the end of the feeler, such filling prevents the turning of the feeler, but when the filling is exhausted or approximates exhaustion, as shown in 90 Fig. 2, then the feeler turns, and in turning forces the trip lever into the position shown in Fig. 2, thereby causing the trip lever to push on the link 43 which, in turn, causes the latch lever 15 to be turned from 100

the position shown in Fig. 1 to the position shown in Fig. 2, thereby bringing the latch tooth 45 in front of the knife edge 46 of the weft hammer. The movement of the 5 weft hammer then forces the latch lever and with it the weft replenishing actuator forwardly and causes replenishment.

In the construction illustrated in Figs. 5, 10 6 and 7, the feeler 26 is provided with the same pivot pin 28, which instead of being inserted directly in the slot 30, is inserted in the head 47 of the slide 48. This slide is a rod which enters a hole 51 in the filling 15 feeler frame 52. The trip lever 53 of this construction is substantially the same in form as in the first described construction, except that the side toward the body 52 of the feeler is provided with a slight recess to receive an enlargement 54. The enlargement 35 on the other side of the feeler is the same as in the former construction, and engages the face 37 of the wall as in that construction. The trip lever is pivoted at 41, as in the other construction. The provision 20 of the slide for carrying the feeler pivot secures better wearing conditions for the pivot.

In both constructions a cover plate 55 is provided which extends along the left hand edge of the wall 37 up over the rear end of 30 the feeler and thence across the rear end of 35 the frame and forwardly and is provided with an ear having a hole which receives the pivot pin 41 in the forward end of the feeler frame.

35 The feeler is light in weight, and is easily moved by the engagement of the yarn therewith without injury to the yarn. The trip lever and the feeler are both held in normal position by the single spring 31, and when 40 the yarn approaches exhaustion, the tipping of the feeler to the left or toward the butt of the bobbin causes the trip lever to be turned to move the latch lever into position to cause weft replenishment. The feeler mechanism 45 is simple in construction and certain in operation, and is easily repaired by removing the cover plate 55 and replacing the parts with new parts in case of wear.

Having thus described the invention, what 50 is claimed is:

1. Filling feeler mechanism for looms having, in combination, a feeler frame provided with a slot, a feeler having a body and an offset filling feeler end, the body having 55 a pivot pin engaging a slot provided with the feeler frame and being adapted to be moved back and forth in the slot by the engagement of the feeler with the filling on the feeler carrier, and being adapted to turn on 60 the pivot when the yarn is sufficiently exhausted to cease to hold the feeler from turning, a trip lever pivoted on the feeler frame with one side normally in engagement with the body of the feeler, said trip lever being

provided with a spring seat projection entering the slot in the feeler frame, a spring interposed between the pivot of the feeler and the spring seat projection of the trip lever normally acting to hold the trip lever against the body of the feeler and the feeler 70 in its rearward position, weft replenishing mechanism, and connections between the trip lever and the weft replenishing mechanism.

2. Filling feeler mechanism for looms having, in combination, a feeler frame provided 75 with a slot, a feeler having a body carrying a pivot pin on its under side adapted to enter the slot in the feeler frame, said feeler having an offset filling feeler end, the offset being in a direction normally tending to turn the filling 80 feeler on the pivot by movement toward the butt of the filling carrier, a trip lever mounted alongside the feeler provided with a spring engaging portion, and a spring in the slot adapted to engage the feeler pivot 85 at one end and the trip lever at the other, normally tending to hold the trip lever and feeler in normal position.

3. Filling feeler mechanism for looms 90 having, in combination, weft replenishing mechanism, a weft replenishing actuator, a latch lever mounted on the actuator, a weft hammer adapted to engage the latch lever when in active position, a filling feeler comprising a supporting frame, a feeler proper having a body mounted to slide back and forth in the frame and provided with an offset filling feeler end adapted to engage the filling on the filling carrier and to be held 95 by the latter from turning motion when filling is present and permitted to turn in the absence of filling on the carrier, a trip lever located alongside the feeler body, a spring interposed between the feeler and trip lever and normally acting directly on each to move 100 the feeler into filling position and the trip lever into non-replenishing position, the feeler body and trip lever being so shaped that when the feeler is turned owing to the failure of the feeler to prevent such turning 105 movement, a portion of the feeler body engages the trip lever and moves it, and a connection between the trip lever and the latch lever acting when the trip lever is turned 110 by the feeler to turn the latch lever to acting 115 position.

4. In a feeler mechanism for looms, the combination of a feeler stand, a side slipping feeler supported by the stand for movement towards and from the front of the loom and for pivotal movement in a direction longitudinally of the shuttle by the frontward pressure and held from such pivotal movement by engagement with the filling until substantial exhaustion of the filling on a 120 detecting beat, a trip device pivoted in fixed position and having a rearwardly extending arm with relation to which the feeler has 125

movements towards and from the front of the loom, a lateral projection extending from the trip device, and a spring interposed between the feeler and the lateral projection of the trip device and acting expansively to hold the rearwardly extending arm of the trip device against the side of the feeler and normally acting to move the feeler to rearward feeling position relative to the trip device, and means connected to the trip device to effect replenishment of filling. In testimony whereof I have signed my name to this specification.

JONAS NORTHROP.
